Adam E. Fisher.

Attorney

UNITED STATES PATENT OFFICE

AXEL NELSON, OF BRISTOL, PENNSYLVANIA

PARACHUTE OPENER

Application filed February 13, 1929. Serial No. 338,504.

This invention relates to a mechanism for opening an aviator's parachute.

The main object of the invention is to provide a means whereby an aviator's parachute will be quickly and positively unfolded or opened and brought into use when the necessity arises to sustain the aviator and provide for his safe descent even though the parachute is brought into use at a low altitude.

10 Another object is to provide a device of this character which will be simple and durable in form and efficient in fulfilling its function.

The foregoing and other objects together with means whereby the same may be carried into effect will best be understood from the following description of a preferred embodiment of the invention taken in connection with the accompanying drawing, in which:

20 Figure 1 is a side elevation of the invention in its folded or inoperative position, the parachute being shown in section.

Figure 2 is a section along the line 2—2 in Figure 1, with the parachute open.

25 Figure 3 is a detail view of the connection between the parachute and one of the spreaders.

Figure 4 is an enlarged section along the line 4—4 in Figure 2.

30 Referring now more particularly to the drawing the reference numeral 1 denotes an elongated tubular cylinder or casing of aluminum or other suitably light material. The said cylinder is provided with diametrically opposite longitudinal slots 2 open at their lower ends and the cylinder is closed at its upper end by a diametrically enlarged cap 3, the said slots 2 terminating short of this cap 3 as shown. The lower end of the cylinder is internally threaded for the reception of a plug denoted generally at 4. An annular spreader carrier or plunger 5 is slidably mounted over the cylinder 1 and has inwardly directed lugs 6 adapted to engage the said slots 2 in this cylinder and project inwardly into the cylinder as shown. An expansion coil spring 7 is braced between these inwardly extended lugs 6 and the plug 4 and is adapted to urge the said carrier 5 upwardly as will be understood. Locking

arms 8 are pivotally depended from the carrier 5 and angular hooks 9 are provided upon the inner sides of these arms adjacent their lower ends. Locking levers 10 are fulcrumed at 11 in the extended flanges 12 of the plug 4, the upper ends of these levers having angular notches 13 in their outer sides to receive the said hooks 9 on the arms 8. The lower ends of the levers 10 are curved inwardly and upwardly at 14 and a release cord 15 is connected to their inner ends so that a downward pull upon this cord will draw the upper ends of the levers 10 inwardly towards the cylinder as will be understood from Figure 2. The levers are normally held in their locking position shown, by a retractile coil spring 16 stretched between the ends of the levers and the plug 4. From the foregoing it will be apparent that the spreader carrier 5 may be drawn downward upon the cylinder 1 compressing the spring 7 until the said hooks 9 upon the locking arms 8 engage the complementary notches 13 in the levers 10 whereby the said carrier will be retained in this lowered position. By a pull upon the release cord 15 the upper ends of the levers 10 will swing inward releasing the carrier and the spring 7 will impel the said carrier upward to the top of the slots 2.

35 The parachute 17 is of conventional construction having the supporting cords 18 which may be secured in any convenient manner to the cap 3 at their upper ends as by tying these ends in suitable apertures in the cap. Spreader arms 19 are pivoted between the ears 20 formed upon the outer periphery of the annulus of the spreader carrier 5 and the opposite ends of these arms are pivotally attached by pins 21 to the lugs 22 formed upon the sleeves 23 which are clamped upon the support cords 18 in the proper position.

40 In use the device is secured upon the aviator's back in any suitable manner with the ends of the said cords 18 secured to the conventional harness about the aviator's body so that when the parachute is opened it will support him. Upon pulling the release cord 15 the carrier will be instantly forced upward as set forth. The spreader arms 19 will thus be swung upward and outward caus-

ing the parachute to be opened as shown in Figure 2 when the carrier 5 reaches the top of the slots 2. One possible method of folding the parachute about the opener is shown in Figure 1, however different methods may be used as found to be best in the use of the device.

While I have herein set forth a certain preferred embodiment of the invention it is understood that I may vary from the same in minor structural details, not departing from the spirit of the invention and within the scope of the appended claims.

I claim:

15. 1. In a device of the character described, a cylinder, a spring set spreader carrier slidably mounted on the cylinder, locking arms depended therefrom, hooks upon the said locking arms, a plug threaded in one end of the cylinder, spring set locking levers fulcrumed upon the said plug, the said levers having notches to receive the said hooks upon the locking arms, a parachute attached to the said cylinder and spreader arms pivotally attached to the said spreader carrier and secured to the said parachute.
20. 2. In a device of the character described, a cylinder, a cap thereon, the said cylinder having slots through its walls, a plug threaded in the end of the cylinder, a spring set spreader carrier slidably mounted on the cylinder, lugs upon the spreader carrier to engage the said slots in the cylinder, locking arms depended from the said carrier, hooks upon the said arms, spring set locking levers fulcrumed upon the said plug and having notches to engage the said hooks on the locking arms, a release cord operatively connected to the said locking levers, a parachute secured to the said cap on the cylinder and a plurality of spreader arms pivoted by their inner ends to the said spreader carrier and attached by their outer ends to the said parachute.
25. 3. In a device of the character described, a cylinder, a spring set spreader carrier slidably mounted in the cylinder, locking arms upon the carrier, spring set locking levers fulcrumed upon the cylinder and adapted to releasably engage the said locking arms, a parachute connected to the said cylinder and spreader arms pivotally attached to the said spreader carrier and secured to the parachute.

In testimony whereof I affix my signature.

AXEL NELSON.
